UNITED STATES PATENT OFFICE.

FRANK B. DAVIDSON, OF MARSEILLES, ILLINOIS, ASSIGNOR TO THE
HOWE & DAVIDSON COMPANY, OF EAST ORANGE, NEW JERSEY,
A CORPORATION OF NEW JERSEY.

PAPER TRAY.

No. 823,847.

Specification of Letters Patent.

Patented June 19, 1906.

Application filed October 10, 1904. Serial No. 228,546.

To all whom it may concern:

Be it known that I, FRANK B. DAVIDSON, a citizen of the United States, residing at Marseilles, in the county of Lasalle and State of Illinois, have invented certain new and useful Improvements in Paper Trays; and I do hereby declare that the following is a full, clear, and exact description thereof, reference being had to the accompanying drawings, and to the letters of reference marked thereon, which form a part of this specification.

This invention relates to improvements in trays made of pasteboard and like flexible material and provided with a flat bottom and with a rim or rim-segments and adapted to be arranged in superposed order within a pail or the like, each tray being adapted to be filled with merchandise and the tray-bottoms constituting horizontal separators to separate the layers of merchandise supported in the trays. Each tray (excepting the lower-most one) is adapted to be supported upon the rim or rim-segment of the next lower tray. In the use of said trays the first one is set in the bottom of the pail either before or after it has been filled, the second tray being similarly filled and set upon the rim or rim-segments of the first or bottom tray, and so on until all the trays are placed in the pail.

Among the objects of my invention is to simplify and reduce the cost of production of such trays; and a further object of the invention is to facilitate the forming of the trays from the blanks and to facilitate their insertion into and removal from the pail.

My invention relates to the complete tray, as well as the blank from which it is made.

As shown in the drawings, Figure 1 is a plan view of a cut and scored blank from which one form of my improved tray is made. Fig. 2 is an enlarged fragmentary perspective view of a portion of the bottom of the tray when set up and showing one of the rim-segments. Fig. 3 illustrates the manner in which said trays are fitted in a pail. Fig. 4 is a top plan view of a tray made generally like that shown in the other figures. Fig. 5 is an enlarged fragmentary perspective view of the tray shown in Fig. 4. Fig. 6 is a horizontal section taken on line 6-6 of Fig. 5.

As shown in said drawings, A, Fig. 1, designates as a whole the blank in flat form

from which the tray shown in Figs. 2 and 3 is made. The central part a of the blank, or that constituting the bottom, is made of generally circular contour and is provided with a plurality of marginal flaps a' , which are separated from the bottom portion by straight score-lines a^2 , the flaps being adapted to be folded upwardly on said score-lines at right angles to the bottom a to constitute rim-segments. Four of such flaps are herein shown, though there may be a greater or less number thereof. Said marginal flaps a' are herein shown as made of triangular form, with their straight bases joined to the bottom at the score-lines a^2 , referred to. The said bases of the triangular flaps extend beyond the score-lines a^2 at the sides of the flaps, and such extensions constitute tongues a^3 , which are separated from the margins of the bottom part by reason of the fact that the inner margins of said tongues are straight and that the marginal parts a^4 of the bottom are curved between said score-lines a^2 . The said tongues a^3 are adapted when the flaps are folded upwardly to constitute the rim-segment referred to to rest with their inner or lower straight margins against the upper face of the bottom, as shown in Fig. 2. When the flap is thus folded upwardly and placed in a pail, the tongues a^3 are curved inwardly to conform to the curvature of said marginal parts a^4 of the bottom. The outer ends of the triangular flaps a' are separated from the body of the flaps by score-lines a^5 , and the terminal ends or tabs a^6 of the flaps are adapted, when the blank is folded to form the tray, to be folded horizontally or at right angles to the vertical or main portion of the flaps, as shown in Fig. 3. The tabs a^6 constitute, in effect, handles which are grasped to handle the tray, as when inserting it into and removing it from a pail or the like, and also constitute, in connection with the vertical rim segments or flaps a' , supports for a superposed tray, as shown in Fig. 3.

In Figs. 4, 5, and 6 I have shown a tray provided with a complete rim comprising, in addition to the rim-segments just described, a strip B, that is interlocked with the said rim-segments, whereby a rim is provided which extends entirely around the tray-bottom. The blank from which the principal part of the tray is made, Figs. 4, 5, and 6, is

identical with the blank A of the first-described tray, with the exception that the main parts of the flaps a' are provided with parallel slits a'' , Figs. 5 and 6, which when 5 the flaps are folded upwardly are vertical, and the rim-strip B is laced through said slits when said flaps are folded upwardly. Preferably the meeting ends of the strip, constituting the endless rim, meet at one of the 10 extensions or tabs in overlapping relation, as shown in Fig. 6, thereby constituting a frictional connection between the ends of the rim-strip, which is sufficient to hold the same in place without resorting to additional fastening means. The terminal tabs a'' of the tray shown in Figs. 4 to 6, inclusive, are of the same general form and perform the same functions as do the like terminal tabs shown in Figs. 1 to 3. In the last-described 15 construction, however, each tray is supported from a subjacent tray throughout its entire periphery. Moreover, in said last-described construction the continuous rim B permits a filled tray being handled without liability of the contents falling from the tray.

I claim as my invention—

1. A substantially circular tray consisting of two pieces of sheet material, to wit, a main part constituting a flat bottom and 20 provided with a plurality of separated marginal flaps which are folded upwardly on score-lines which meet the curved margins of the bottom at the sides of the flaps, and a strip which extends around the margin of the 25

bottom, with its lower edge in contact with 35 said margin, and with said flaps forms a rim therefor, said strip being inserted through slits in said flaps.

2. A tray having a flat circular bottom and four marginal triangular flaps arranged equi- 40 distant from each other, and folded upwardly from said bottom at right angles thereto, said tray comprising a blank of substantially rectangular form having its side margins between its corner portions of convexly-curved 45 form to constitute parts of the margin of the circular flat bottom, and its corner portions shaped to form the four triangular flaps, which flaps are separated at the sides thereof from the curved marginal parts of the bottom, by notches, the inner ends of which meet the lines of fold at the bases of the flaps, 50 said notches forming on the flaps lateral extensions the inner margins of which, in the blank, constitute straight continuations of 55 said lines of fold, and which in the finished tray are bent inwardly to conform to the curvature of the said curved marginal parts of the bottom.

In testimony that I claim the foregoing as 60 my invention I affix my signature, in presence of two witnesses, this 22d day of September, A. D. 1904.

FRANK B. DAVIDSON.
